ABSTRACT: A method of obtaining an improved octane rating by hydroisomerization which involves separating a stock into two portions, individually hydroisomerizing the portions for olefin conversion and combining the two hydroisomerized streams.

HYDROISOMERIZATION OF MOTOR FUEL STOCKS

This invention relates to motor fuel production.

In one of its more specific aspects, this invention relates to hydroisomerization of stocks in the motor fuel range for the purpose of quality improvement.

Catalytically cracked and pyrolysis gasolines normally contain olefins and diolefins which have a deleterious effect on the gasoline inasmuch as they tend to form gums. Such materials are particularly prevalent in certain deisopentanized stocks, derived from the cracking, having an initial boiling point of about 100° F. and an end point of about 400° F. While the total stock can be hydroisomerized for olefin, acetylene, and diolefin conversion to other forms of hydrocarbons, it has now been determined that improved results are realized if this raw gasoline is divided into two portions, each of which is individually hydroisomerized, the two portions being recombined thereafter to provide a motor gasoline blending stock. The method of this invention provides such a process.

According to the method of this invention there is provided a process for hydroisomerizing a cracked gasoline containing olefins which comprises separating the stock into two portions of different boiling ranges, hydroisomerizing each portion individually over different hydroisomerization catalysts and combining the hydroisomerized streams to produce a gasoline blending stock having a higher octane number than can be produced by hydroisomerizing the total stock over either of the catalysts.

The method of this invention, in one of its aspects, contemplates treating cracked gasoline obtained by cracking a stream comprising substantially virgin gas oil over a cracking catalyst such as silica-alumina, molecular sieve, etc. in a fluid catalytic cracking unit. This product stream will comprise C₅'s through about 400° F. end point material, and will have an olefin content of about 55 percent and a diolefin-acetylene content of about 1 percent.

The catalytically cracked gasoline to be isomerized is divided into two portions. The first portion is a 200° F. end point material and comprising olefinic materials. The second portion is a 200° F.-400° F. E.P. cut comprising substantially aromatics and some small amount of olefins. Both portions contain diolefins.

Accordingly, it is an object of this invention to provide an improved method of hydroisomerizing olefins present in cracked gasolines.

It is another object of this invention to provide an improved motor fuel blending stock.

This invention can be carried out in any of the usual processing sequences, including series or parallel flow of the individual reactants. Catalysts suitable for promoting the reactions involved are the conventional palladium on alumina-type catalysts and the nickel sulfide-type catalysts.

Palladium on alumina catalysts can be employed in any convenient form, such as pelleted or spherical shapes. The catalysts will contain about 0.005 to about 1.0 weight percent palladium on alumina, preferably about 0.01 to about 0.1 percent. The alumina will be of controlled pore diameter and will contain about 41.5 weight percent alumina. It will weigh about 40-52 pounds per cubic foot, will have a surface area of about 340-350 square meters per gram, a pore volume of about 0.50 to 0.60 milliliters per gram, and a pore diameter of about 60 to about 70 Å. While this catalyst will be spoken of herein as the palladium catalyst, it is to be understood that equally suitable catalysts include the noble metals of Group VIII of the Periodic Table of Elements, *Handbook of Chemistry and Physics*, Chemical Rubber Company, 45th Edition (1964), page B-2, and include ruthenium, rhodium palladium, osmium, iridium and platinum on such supports as alumina, silica-alumina, glass beads and carbon.

The second catalyst employed in the method of this invention will be referred to herein as the nickel sulfide catalyst. It will comprise a solid acid isomerization catalyst containing a sulfide of one or more of the metals of the left-hand column of Group VI including chromium, molybdenum, tungsten and/or a sulfide of one or more of the metals of Group VIII, for exam-

ple, iron, cobalt, nickel, of the Periodic Table. Such catalysts contain the metal sulfide in the range of about 0.5 to about 15 percent by weight based upon the total catalyst, the support being any suitable support such as silica, alumina, etc. Both the catalysts employed herein are well known and their preparation and use is described in the prior art.

This invention contemplates the separation of the cracked product into two individual stocks which are individually hydroisomerized. Any suitable method of separating the cracked stock into the individual stocks is satisfactory, fractionation being preferably employed to produce a first stock, the "200° F. end point stock" having an end point of from about 200°-250° F., and a second stock, the "400° F. end point stock" having an IBP of from about 200°-250° F. and an end point of about 375°-450° F.

The 200° F. end point stock is contacted with a palladium catalyst in a catalytic contacting zone in substantially the vapor phase to hydrogenate the diolefins and to isomerize the olefins to internal olefins. Generally the reaction is conducted at a temperature of about 200°-300° F., at a pressure of about 10 to 200 p.s.i.g., in the presence of hydrogen in an amount of from about 2 to about 10 mols of hydrogen per mol of diolefins plus acetylenes, at a liquid space velocity, vol./vol./hr., of from about 1 to about 4.

The 400° F. end point stock is contacted in a catalytic contacting zone with the sulfide catalyst in substantially the vapor phase at a temperature of about 400°-750° F., at a pressure of about 200-1000 p.s.i.g. in the presence of hydrogen in an amount from about 2 to about 10 mols of hydrogen per mol of hydrocarbon, at a liquid space velocity, vol./vol./hr., of about 0.5 to 2.

The individually isomerized stocks are combined to produce a motor fuel blending stock.

The practice of the method of this invention produces a motor fuel blending stock having a higher octane member than is obtainable when treating the unproportioned cracked stock, as such, with either of the catalysts under comparable conditions. This is indicated by the following runs in which a catalytically cracked gasoline containing C₅ through 400° F. end point material, having an olefin content of about 55 volume percent, a diolefin-acetylene content of about 1 percent, and a research octane number, with 3 cc. of tetraethyl-lead per gallon, of 97.0, was treated in its entirety with the two catalysts concerned under the following conditions.

	Conditions	Palladium Alumina Catalyst	Nickel Sulfide Catalyst
50	Temperature, °F.	500	600
	Pressure, p.s.i.g.	50	500
	Space Velocity, vol./vol./hr.	2	1
	Hydrogen/Hydrocarbon Mol Ratio	0.05*	6
	Research Octane Number, 3 cc.		
55	Tetraethyllead	98.0	97.5

*Hydrogen/Diolefins plus Acetylenes Mol Ratio is 5:1

In contrast to this method and in accordance with the method of this invention, the same stock was fractionated to produce a C₅-200° F. end point material which was isomerized with a palladium catalyst in accordance with the procedure described below, and 200-400° F. cut which was treated with the nickel sulfide catalyst under the conditions indicated below. The octane number indicated is on the stream after the treated portions were recombined in their entirety.

Conditions	Stock C ₅ -200° F. End point	Stock 200-400° F. End Point
Catalyst	Palladium-alumina	Nickel Sulfide
Temperature, °F.	250	600
Pressure, p.s.i.g.	50	500

Space Velocity, vol./vol./hr.	2	1
Hydrogen/Hydrocarbon		
Mol Ratio	0.05*	6
Blend, Research Octane Number, 3 cc.		5
Tetraethyllead	98.5	

*Hydrogen/Diolefins plus Acetylenes Mol Ratio is 5:1.

aromatics;

- b. a hydroisomerizing said first portion by contacting said first portion with hydrogen and a catalyst consisting essentially of a supported noble metal of Group VIII of the Periodic Table to hydrogenate said diolefins and to isomerize said olefins to internal olefins and to produce a first hydroisomerized stream;
  - c. hydroisomerizing said second portion by contacting said second portion with hydrogen and a catalyst consisting essentially of a supported sulfide of a metal of the left-hand column of Group VI of the Periodic Table to produce a second hydroisomerized stream;
  - d. combining said first hydroisomerized stream and said second hydroisomerized stream; and,
  - e. recovering the combined stream as said produce.
2. The method of claim 1 in which said cracked gasoline has an olefin content of about 55 percent and a diolefin-acetylene content of about 1 percent.
3. The method of claim 1 which said first portion is hydroisomerized by contact with a catalyst consisting essentially of supported palladium and said second portion is hydroisomerized by contact with a catalyst consisting essentially of supported nickel sulfide.
4. The method of claim 1 in which said first portion is hydroisomerized in the vapor phase at a temperature within the range of about 200-300° F. at a pressure of about 10 to 200 p.s.i.g. and a said second portion is hydroisomerized in the vapor phase at a temperature in the range of about 400-750° F. at a pressure of about 200-1000 p.s.i.g.
5. The method of claim 3 in which said first portion is hydroisomerized at a temperature of about 250° F. at a pressure of about 50 p.s.i.g., at a space velocity of about 2 and at a hydrogen to hydrocarbon mol ratio of about 0.05 and said second portion is hydroisomerized at a temperature of about 600° F. at a pressure of about 500 p.s.i.g., at a space velocity of about 1 and at a hydrogen to hydrocarbon mol ratio of about 6.

UNITED STATES PATENT OFFICE

CERTIFICATE OF CORRECTION

Patent No. 3,619,408

Dated: November 9, 1971

Lewis G. Larson

It is certified that error appears in the above-identified patent and that said Letters Patent are hereby corrected as shown below:

Column 4, line 2, delete the word "a"; line 15, the word "produce" should read
--- product ---.

Signed and sealed this 11th day of April 1972.
